PIPE WORKING TOOL

Arthur S. Gould, Lakewood, William M. Emery, Cleveland Heights, and Ralph E. Hyde, Cleveland, Ohio, assignors to The Oster Manufacturing Company, Cleveland, Ohio, a corporation of Ohio

Application March 16, 1939, Serial No. 262,214

6 Claims. (Cl. 10—89)

This invention relates to pipe-working apparatus in the form of a rigid housing which serves both as a support for certain mechanism therein and as a work bench. Although primarily for pipe-working it is adapted to other purposes, as will be apparent from the detailed description of a preferred embodiment. Thus the word "pipe" is used hereafter by way of example, indicating the most usual work-piece, and not by way of limitation.

This invention is directed specifically to the following purposes, although the recital of purposes is not intended to exclude others not mentioned:

15 To provide a stand of great rigidity but light weight; to afford support and protection for a motor-driven pipe chuck; to permit the use of a motor which is particularly suitable for such work but which requires ample ventilation; to furnish 20 a long-span steady rest for pipe being rotated by the chuck; to permit the use in power work of ordinary hand tools such as die stocks and cutters; to combine a maximum of protection and covering for all moving parts with complete 25 accessibility for insertion and removal of work; to drive the chuck at the most advantageous point without sacrifice of length of bearings; to arrange the machinery compactly within the stand; and to obtain various further benefits and advantages which will be appreciated by those skilled 30 in the art.

The following description is illustrative of a preferred form without excluding such modifications and alterations thereof as come within the 35 principles of our invention.

In the accompanying drawings

Fig. 1 is a vertical longitudinal section substantially on the median axial plane of the chuck, with certain parts in elevation, the view except 40 for elevational parts, being indicated by the plane 1—1 of Figs. 2 and 7, looking in the direction of the arrows;

Fig. 2 is a vertical transverse section on the broken plane 2—2 of Fig. 1, with some parts in 45 elevation, looking in the direction of the arrows;

Fig. 3 is a perspective of the mounting bracket; Fig. 4 is a stand detail in section on the plane 4—4 of Fig. 2, in the direction of the arrows;

Fig. 5 is a front elevation of the apparatus in 50 operation, on a reduced scale;

Fig. 6 is a side elevation of the apparatus, on a further reduced scale;

Fig. 7 is a rear elevation of the apparatus, looking in the direction of the arrow 7 of Fig. 1 and 55 showing one form of steady rest;

Fig. 8 is the same view as Fig. 7, but showing a modified steady rest; and

Fig. 9 is a fragmentary view on the plane 9—9 of Fig. 8, showing the modified steady rest of Fig. 8, omitting some interior features for simplicity.

As best seen initially in Figs. 5 and 6 the preferred embodiment of our invention comprises a housing in the general shape of a truncated pyramid, with wide-spreading leg sockets 11—11 and 12—12 into which pipe or rod legs may be inserted. The truncated pyramid is preferably a welded unitary structure with outwardly sloping sides 13, 14 and back 15, vertical front 16 and flat top 17, with the rear legs 12 directly incorporated as both exterior and interior corner structure, as best seen in Fig. 4. To increase the rigidity of the housing, and to protect the housed mechanism from below, the sides and ends are inwardly flanged as at 23, 24, 25 and 26; such flanges, however, do not extend inward far enough to interfere with ventilation or with access from beneath. The leg sockets pass through such flanges and are welded thereto.

The mechanism housed consists of the chuck 25 31, motor 32, and connecting gearing, and these are carried in a close and compact arrangement by a special bracket 33 suitably fastened beneath the flat top 17 and preferably slightly spaced therebelow by pads 34. This spacing is visible at 30 35, Figs. 1 and 2.

The chuck 31 consists in detail of a long sleeve 38 rotatable in a long bearing 39 in the bracket 33, and including at its forward end clamping arrangements such as studs 40 actuatable by scroll plate 41 having pin wrench sockets 42 which project forward through a clearance opening in the front 16. The sleeve 38 is suitably held against endwise movement, a shoulder 44 at one end and set ring 45 at the other being illustrated for this 40 purpose. A reverse flange 46 springing from the forward end of the sleeve carries a gear ring 47 by which the chuck receives power from the motor 32 through a gear box 48 and small pinion 49, here shown as having seven teeth. This gear ring is especially protected from beneath by the flange 26.

The bracket 33 is a unitary member stiffened by double sides 51, 52 and cross webs 53, 54, 55, thus preserving the alignment of moving parts 50 and accuracy of gear engagement as well as alignment of the pipe by means of the studs 40 and a support 56 in the rear wall 15. The cross webs 53, 54 and the forward portions of the side walls 51, 52 extend downwardly below the general level 55

of the rear part of the bracket, and join the chuck bearing 39 which extends considerably forward of the web 53, and thereby permits certain advantages in the drive arrangement, as hereafter described.

Horizontal and vertical side lugs 57 and 58, integral with and extending from the side 51 at rear and front respectively afford support for the motor 32 and gear box 48, thus disposing the 10 motor shaft, the reduction gearing, the pinion 49, and the chuck sleeve 38 all in paraxial relationship.

Among the advantages of keeping the pinion small are that the motor can be placed with shaft 15 parallel to the spindle axis, which enables the use of side-meshing gears throughout, avoiding the more expensive and less efficient gearing, such as bevels and so on, which angular shafting relationships would necessitate. Another favorable 20 result is that the motor 32 and the chuck 31 can be nested close side-by-side with much of the motor extending behind the chuck, as seen in Fig. 1, thus economizing space in the direction of width (see Fig. 2) and which enables the mechanism 25 to be fitted into the narrow top space of the stand. At the same time the shallowness of the rear part of the bracket 33 allows free circulation of air to the motor 32 for cooling. All this is advantageous in a portable outfit which 30 must be taken from place to place and set up in small spaces.

A particular benefit in respect to the motor is that a series wound motor is best for this sort of work, but requires ample ventilation. The 35 advantage of the series motor is that as the load increases the power increases but the speed reduces. It will thus turn a large pipe at fewer revolutions per minute than a small one, with the result that the foot/minute cutting speed is 40 approximately constant irrespective of the size of pipe being worked. The necessary ample ventilation for such a motor is obtained by keeping the bracket out of the way and by having the stand wide open at the bottom although it is 45 stiffened by the flanges 23 to 26 and the gear 47 is protected by the flange 26.

A steady rest for pipe, rod, or the like P being worked is provided at the aperture in the rear wall 15. This may take the form of the Y 56, 50 with a wide horizontal pipe-contacting face at 60, and holding-down finger 61, both adjustable up and down upon the rear wall 15. An alternative form shown in Figs. 8 and 9 consists of a plate 65 pivoted at 66 upon the rear wall 15 below the aperture and having a series of elongated holes 67 corresponding to usual pipe sizes, which can be brought into central alignment with the axis of chuck 31 by rotation about the pivot 66, and 60 latched in place by the latch 68 in notches 69. The plate 65 is of substantial thickness, and the edges of the holes 67 are formed at the proper angle to give a broad horizontal edge such as 71 for the pipe or other workpiece. The plate 65 65 may carry index numbers adjacent the latch notches 69 to indicate the pipe size for which set. It is intended that the pipe, rod or the like being rotated in the spindle will fit the rear support with easy tolerance and turn therein with 70 little friction, and oil can readily be applied thereto if needed.

Side bars 70, slidably endwise in eyes 72 welded to the stand structure, are useful as carrying handles, and serve as stops for cutters, die stocks 75

or other tools T, Figs. 1 and 5, working on a pipe, rod or other revolving workpiece P.

On account of the rigidity of mounting of the spindle and motor the weight of rearwardly overhanging work can never throw the gearing out of alignment, but it is nevertheless desirable to keep the work lined up across as long a span as is readily available, and in the present stand this is accomplished over a span considerably greater than spindle length by means of the 10 rear guides or steady rests. Such steady rests are carried by the rigid box-like stand body, and not upon any outside foundation and consequently are aligned with the chuck jaws as long as the stand is not distorted from its shape; this is because the chuck jaws are also aligned with the stand body inasmuch as the bracket of Fig. 3 is secured to such body. The stand is a compact, sturdy and rigid unit, which may be 15 put on a bench, but the more usual use will be to put pipes into the leg sockets to bring it to proper height. Even if the pipe leg extensions are somewhat yielding, any workpiece supported between the chuck jaws 41 and the rear steady 20 rest forms part of a rigid system with the stand organization, and the parts of the organization are not changed in their relations to one another even if the pipe legs wobble. Thus good and accurate work can be done by the mechanism 25 even if the stand is indifferently supported. 30

Our stand is chiefly intended for use in portable sizes, such as can readily be carried by two men. It might of course be put on a wheeled carriage or on a bench. An electric motor is 35 the preferred drive although other power might be substituted. Electrical switches, connections, speed controls and so on will be of appropriate character and are not illustrated.

The chuck and rear steady rest being below 40 instead of on top of the table 17 gives a longer span for support of the pipe on account of the spread of the back wall 15. Furthermore it leaves the top 17 clear for attachment of a vise or other tool (not shown) for use as a work-bench, and so on. 45

The foregoing description and the drawings therewith are disclosures of preferred embodiments of our invention, not intended to exclude modifications which apply the same principles. 50

We claim:

1. A cutting and threading tool comprising in combination a support, a bracket dependent therefrom, said bracket comprising a relatively shallow cantilever portion and longitudinally spaced downwardly directed webs, a bearing having its front end integral with the forward one of said webs, and its rear end integral with the back one of said webs, a side lug formed on the rear end of said cantilever, and another side lug formed on said first-named web, said lugs constituting a motor support, a rotatable chuck in said bearing and a driving motor for said chuck supported by said lugs, driving connections from said motor to said chuck, means connecting the said bracket to said support at the forward web and at the rear of said cantilever, protective skirts downwardly directed at the sides of said support, edges defining openings in said skirts at front and rear, the front opening providing clearance for chuck clamping mechanism and the rear opening providing entrance for a work piece, and inwardly directed flanges underneath said skirts underlying all exposed moving parts of said driving connections. 65

2. Apparatus of the character described com- 75

5 prising in combination a stand including a top plate and support therefor, a bracket beneath said plate, said bracket consisting of a top arm secured to said plate and a vertical downward arm at one end of said top arm, a horizontal side lug at the other end of said top arm, a vertical side lug upon said downward arm on the same side as said horizontal lug, paraxial bearings in said vertical arm and said vertical lug respectively, a revolute chuck in the bearing in said downward arm and a drive shaft for said chuck in the bearing in said vertical lug.

10 3. Apparatus of the character described comprising in combination a frusto-pyramidal stand and a unitary cast suspension element supported therein, a chuck and drive means for the same carried by said suspension element above the level of the bottoms of the sides of said stand, said chuck including a scroll plate having a handle exposed through a side of said stand, and side bars supported on said stand and adapted to extend beyond said stand to engage a tool upon a work piece held by said chuck.

15 4. A pipe working bench comprising in combination a top and walls comprising a substantially frusto-pyramidal structure, diverging legs in said structure, a work turning chuck supported beneath said top, work engaging jaws in said chuck near the front wall of said structure, a work steadyng device near the back wall of said structure, said device comprising a disk, a pivot connecting said disk to said rear wall of said structure, a plurality of apertures in said disk fitted to specific pipe sizes, and locking means for selectively positioning any of said apertures in central axial alignment with the axis of said chuck.

5 5. A pipe working bench comprising in combination a top and walls comprising a substantially frusto-pyramidal structure, diverging legs in said structure, a work turning chuck supported beneath said top, work engaging jaws in said chuck near the front wall of said structure, a work steadyng device near the back wall of said structure, said device comprising a disk, a pivot connecting said disk to said rear wall of said structure, a plurality of apertures in said disk fitted to specific pipe sizes, and locking means for selectively positioning any of said apertures in central axial alignment with the axis of said chuck, and indicia operatively related to the locking means for said disk, thereby indicating the pipe size for which the disk is set.

10 6. A pipe working machine comprising a truncated pyramidal four sided housing, the smaller top end being closed and the larger bottom being open, sockets near the corners thereof adapted to receive supporting legs, a casting attached to the inside of the top, a motor and gear reduction aligned and positioned by said casting, a gripping chuck including a hollow spindle with a large gear fast thereon journaled in said casting and aligned to mesh with said gear reduction, said chuck extending through one side of said truncated pyramid, and means supported by said pyramid substantially parallel to said spindle to resist the turning with the pipe of tools upon the pipe, but allowing movement of said tools longitudinally with the pipe.
